ROBERT RENNIE, OF SCOTIA, NEW YORK, AND HAL R. STAFFORD, OF PLAINFIELD,
NEW JERSEY.

DRIFTING-VALVE FOR LOCOMOTIVES.

1,079,514.

Specification of Letters Patent.

Patented Nov. 25, 1913.

Application filed September 27, 1913. Serial No. 792,099.

To all whom it may concern:

Be it known that we, ROBERT RENNIE, of Scotia, in the county of Schenectady and State of New York, and HAL R. STAFFORD, of Plainfield, in the county of Union and State of New Jersey, have jointly invented a certain new and useful Improvement in Drifting-Valves for Locomotives, of which improvement the following is a specification.

The object of our invention is to provide means, of simple and inexpensive construction and ready applicability in locomotives of any of the present constructions, whereby a graduated volume of steam may be automatically admitted to the valve chests or cylinders of a locomotive engine, when "drifting" or running with its throttle closed, under the influence of inertia or gravity, the quantity of steam so admitted being regulated proportionally to the speed of the locomotive so as to prevent the formation of a partial vacuum in the valve chests and cylinders, and the admission of steam being so directed as to insure the feed of the lubricating material in the most effective manner.

The improvement claimed is hereinafter fully set forth.

30 In the accompanying drawings: Figure 1 is a side view, partly in section, of a locomotive engine, illustrating an application of our invention; Fig. 2, a vertical central section, on an enlarged scale, of a drifting valve mechanism embodying our invention; and, Fig. 3, a transverse section, on the line *a a* of Fig. 2.

In the operation of locomotives on long descending grades, it is the practice to close the throttle valve, thereby shutting off the supply of steam to the valve chests, under which condition the movements of the pistons produce partial vacuums in the cylinders, resulting in the injurious induction of hot gases and cinders into the cylinders, and by reason of the cessation of steam supply, they are insufficiently lubricated and their inner surfaces, as well as those of the packing rings and piston heads, are rapidly deteriorated by a gummy deposit of oil and dirt. This latter objectionable result is particularly serious in the case of locomotives using superheated steam. In order to prevent this objectionable induction of smoke

box gases and cinders above mentioned, three different types of devices have heretofore been applied, viz: (a) check valves opening inwardly to the distribution valve chests, and permitting the ingress of atmospheric air during the periods that a partial vacuum is otherwise formed therein; (b) by-pass or circulating appliances, whereby direct communication is established between the opposite ends of the cylinders, so that the gases therein are caused to flow past or around the pistons at each stroke, instead of being alternately expelled and drawn in through the exhaust passages; and (c) auxiliary or drifting throttle valves, by means of which a small quantity of steam is admitted to the valve chests, when the locomotive is "drifting" or running with the main throttle valve closed.

Appliances of the air admission type (a) are objectionable by reason of involving, in their operation, a rapid and destructive change in temperature of distribution valves, pistons, bushings, etc., due to the introduction of air, at the temperature of the atmosphere, into passages which are highly heated by the steam, especially when superheated steam is used, thereby causing cracking or breaking of parts if sufficient air is admitted to prevent the induction of smoke box gases, or failure to prevent such induction if the supply of air is sufficiently restricted to minimize the rapid change of temperature.

The objection to by-pass appliances, type (b), consists in the inability of the gases circulated from one to the other end of the cylinders, to dissipate or carry off the heat generated by the friction of the moving parts, so that a sufficient rise in temperature may take place to destroy the oil or other material used for lubrication. Appliances of this type are also subject to the objection of preventing the formation of a compression cushion at the ends of the stroke for relieving the strain on the crank pin due to the inertia of the reciprocating parts, the presence of which cushion is a matter of importance in large locomotives drifting at comparatively high speed.

Auxiliary drifting valves, type (c), as ordinarily constructed, are incapable of graduating the quantity of steam supplied, proportionately to the speed of the locomo-

tive, and subject to the risk of causing accidents by failure to be closed when the locomotive is stopped.

Our invention is designed to accomplish 5 the useful results possible to be derived from appliances of the several types referred to, without being subject to the objections there- to above stated.

Referring to the drawings, in the practice of our invention we provide, in connection with each of the cylinders, 1, of the locomotive, a valve chest or casing, 2 having, on its lower end, a nozzle or tubular extension, 2^a, which is threaded to engage a 15 correspondingly threaded opening at one end of the cylinder, or, as shown, in the wall of one of the steam induction ports, 1^a, of the cylinder. The most convenient location for this purpose is ordinarily that shown 20 in Fig. 1, to wit, in that portion of the induction port which is formed around one of the bushings, 3^a, of the valve chest, 3, in which the distribution valve 4, which, in this instance, is of the piston type, reciprocates. The valve casing, 2, may, however, 25 be connected with the cylinder, or with the induction port at any other point in the length of the latter which may be preferred.

The upper end of the valve casing, 2, is 30 closed by a removable head, 2^b, which is secured to the casing by studs, 5, and nuts, 5^a. An enlarged piston chamber, 2^c, is formed in the casing below the head, 2^b, and a partition, 2^d, extends across the casing and 35 separates the piston chamber, 2^c, from the bore of the tubular extension, 2^a. A valve chamber, 2^e, which is closed at its top by a removable cap, 2^f, is formed in the head, 2^b, and a pipe, 6, leads from the steam space 40 of the boiler into the valve chamber, 2^e, said pipe being preferably connected to a steam supply turret, or small dome on the boiler, and controlled by a valve within convenient reach of the engineman, in the ordinary manner of auxiliary steam supply pipes.

A pipe, 7, leads from the upper portion 45 of the piston chamber, 2^c, to the steam supply space of the distribution valve chest, 3, the connection of said pipe being preferably, 50 as shown, made to the steam supply pipe, 3^b, which leads from the boiler to the distribution valve chest, and its outlet being located adjacent to that of the lubricant feed 55 pipe, 8, in the pipe, 3^b, in order that the steam discharged from it may break up and disseminate the lubricant entering through the pipe, 8.

Communication between the piston chamber, 2^c, of the casing, and the valve chamber, 2^e, of the head, 2^b, is controlled by a 60 valve, 9, governing an opening in the inner wall of the head and having a fluted or chan- neled stem, 9^a, extending through said open-

ing into the piston chamber, 2^c. A properly 65 packed piston, 10, is fitted in the piston chamber, 2^c, below the opening of the pipe, 7, thereinto, said piston, when actuated by pressure on its lower side, abutting against the stem, 9^a, of the valve, 9, and unseating 70 said valve.

A hardened steel valve seat, 11, through which extends a central passage, 11^a, is fitted in the partition, 2^d, of the casing, 2, said valve seat abutting, on its upper side, 75 against an open ended cylindrical guide, 12, which is perforated by a plurality of peripheral openings. The opposite end of the guide, 12, abuts against, and is closed by, a plate, 13, which is held in position by 80 a screw cap, 14, a packing ring, 14^a, being interposed to insure a tight joint. A leakage port, 15, extends through the partition, 2^d, adjacent to the valve seat, the upper end 85 of said port being closed by a screw plug, 15^a, through which a passage of smaller diameter than the leakage port is formed.

The passage, 11^a, of the valve seat, 11, is controlled by a check valve, 16, fitting truly 90 in the guide, 12, said valve being adapted to 90 be unseated by the action of pressure upon its lower side from the tubular extension, 2^a, of the casing, and being chambered out, as shown, to reduce its weight and extend the capacity of the cushion chamber which 95 is formed within the guide, 12, between the upper end of the valve, 16, and the plate, 13.

In the operation of the appliance, when the locomotive is running with throttle open, the pressure in the cylinders rarely rises 100 above that in the distribution valve chests, and the valve chest pressure, acting through the pipes, 7, on the tops of the pistons, 10, in conjunction with the boiler pressure in the valve chambers, 2^e, acting on the tops of the 105 valves, 9, prevents said valves from being unseated, so long as the pressure in the piston chambers, 2^c, below the pistons, 10, is equal to, or less than, the pressure above them. When the throttle is closed, and the main 110 cylinder pistons and distribution valves continue their cyclic motions, the pressure in the distribution valve chests immediately reduces to that of the atmosphere, or less, and during the compression periods of the 115 piston strokes, a pressure or plenum is created in the cylinders, which, through the tubular extensions, 2^a, of the valve casings, 2, and the passages, 11^a, of the valve seats, 11, unseats the check valves, 16, and passing into the piston chambers, 2^c, raises the pistons, 10, thereby unseating the valves, 9, and admitting steam from the boiler to the distribution valve chests, through the pipes, 7. The valve 9 and 16, piston, 10, 120 and leakage port, 15, are properly proportioned to admit sufficient steam to the distribution valve chests to maintain approxi- 125

mately atmospheric pressure therein. When the locomotive is stopped, there will be only atmospheric pressure in the tubular exten-
 5 sions, 2^a, and the entrapped fluid in the piston chambers, 2^c, will escape therefrom through the leakage ports, thereby permitting the pistons, 10, to fall to their lowest position, and the valves, 9, to seat themselves, and preventing further flow of boiler steam to the distribution valve chests.

We claim as our invention and desire to secure by Letters Patent:

1. In a drifting valve appliance for locomotives, the combination of a valve controlling the supply of steam from a locomotive boiler to a steam cylinder, independently of the main steam supply pipe, a piston adapted to unseat said valve, and means, automatically operable by the cessation of 20 main steam pipe supply, for admitting cylinder pressure to said piston.

2. In a drifting valve appliance for locomotives, the combination of a passage establishing communication between a locomotive boiler and a steam cylinder, independently of the main steam supply pipe, a valve controlling said passage, a piston adapted to unseat said valve, and a check valve subject to cylinder pressure and controlling the admission of said pressure to the piston.

3. In a drifting valve appliance for locomotives, the combination of a valve casing having connections to the steam space of a locomotive boiler, to a locomotive cylinder, 35 and to a distribution valve chest, respectively, a valve in said casing, controlling communication between the boiler connection and the valve chest connection, and means for unseating said valve by pressure 40 from the cylinder connection.

4. In a drifting valve appliance for locomotives, the combination of a valve casing having connections to the steam space of a locomotive boiler, to a locomotive cylinder, 45 and to a distribution valve chest, respectively, a valve chamber in said casing continuously open to the boiler connection, a piston chamber in said casing continuously open to the valve chest connection, a valve 50 controlling communication between the valve chamber and the piston chamber, a piston fitting in the piston chamber and adapted to unseat said valve, and a valve controlling the admission of pressure from

the cylinder connection to the piston chamber. 55

5. In a drifting valve appliance for locomotives, the combination of a valve casing having connections to the steam space of a locomotive boiler, to a locomotive cylinder, 60 and to a distribution valve chest, respectively, a valve chamber in said casing continuously open to the boiler connection, a piston chamber in said casing continuously open to the valve chest connection, a valve 65 controlling communication between the valve chamber and the piston chamber, a piston fitting in the piston chamber and adapted to unseat said valve, a valve controlling the admission of pressure from the cylinder connection to the piston chamber, and means for releasing pressure from the piston chamber upon the closure of said valve.

6. In a drifting valve appliance for locomotives, the combination of a valve casing having connections to the steam space of a locomotive boiler, to a locomotive cylinder, and to a distribution valve chest, respectively, a valve chamber in said casing continuously open to the boiler connection, a piston chamber in said casing continuously open to the valve chest connection, a valve 75 controlling communication between the valve chamber and the piston chamber, a piston fitted in the piston chamber and adapted to unseat said valve, a partition interposed between the piston chamber and the cylinder connection, a valve seat fixed in said partition and having a through passage, 80 a peripherally perforated guide fitting on said valve seat, a check valve working in said guide and controlling the through passage of the valve seat, a plate closing the end of the guide farther from the valve seat and providing a cushion 85 chamber within the guide, and a leakage port extending, through the partition, from the piston chamber to the cylinder connection. 90
